UNITED STATES PATENT OFFICE.

JOHN A. STEFFENS, OF BALTIMORE, MARYLAND, ASSIGNOR TO U. S. INDUSTRIAL
ALCOHOL CO., A CORPORATION OF WEST VIRGINIA.

APPARATUS FOR OBTAINING ABSOLUTE ALCOHOL.

Application filed April 5, 1921. Serial No. 458,834.

My invention relates particularly to an apparatus designed to obtain alcohols having a high strength by removing water from the same but it has especial reference to the 5 production of absolute alcohol.

The object of my invention is to provide an apparatus whereby alcohols may be separated from water and especially by means of which absolute alcohol may be obtained 10 in accordance with a commercially practicable system.

More particularly, the object of my invention is to provide an apparatus based upon the utilization of a third liquid which 15 is miscible with the alcohol but substantially immiscible with water and which is of such a character that when the three constituents are present vapors of the same are evolved by distillation containing a considerable percentage of water and the third liquid so that 20 all the water and the third liquid may be removed in this way from the residual constituent, which is the alcohol. The evolved vapors are comprised of a ternary mixture 25 of three constituents. This third liquid may be of any one of a number of different compounds, such, for example, as benzol, carbon tetrachloride, hexane, etc., but I prefer to use benzol.

One of the objects of my invention is to 30 avoid the necessity of using a large amount of benzol in carrying out the apparatus.

A further object is to so arrange the apparatus as to enable a close regulation there- 35 of to be obtained, inasmuch as in my apparatus the dehydration of the alcohol is carried out in a column, the upper portion of which is fed continually with a quantity of the condensate of fixed composition passing 40 out of the top of the tower, as a condensate rich in water is obtained with a compara- tively small load being placed upon the auxiliary apparatus and as the alcohol evolved in the form of vapor is returned to the tower 45 continually in the form of a liquid having a fixed composition obtained by a uniform rectification of the recovered alcohol.

Again, another object is to operate the apparatus so that a drier benzol is obtained 50 owing to the separation of the condensate before introducing water into the same.

A further object is to so arrange the system as to enable the several operations to be carried out continuously, but so that the 55 several operations may be carried out large-

ly independently of the remaining operations, thus enabling the operator of the system to recover in case at any time any one of the operations does not function. This is brought about especially by reason of the 60 complete removal of the benzol from the distillate prior to the rectification of the dilute alcohol. By reason of these features in my apparatus the system may be operated continuously. 65

Further objects will appear from the detailed description thereof contained herein-after.

While my invention is capable of embodiment in many different forms, I have shown 70 only one form of the same in the accompanying drawings, in which—

The figure is a diagrammatic representa- 75 tion of an apparatus made in accordance with my invention.

In the drawings, I have shown a valved inlet pipe 1 for feeding continuously into the apparatus an alcohol mixed with water, and which, by way of example, may feed to the system ethyl alcohol having a strength 80 of 95%. Leading into the pipe 1 there is a valved supply pipe 2 for supplying initially the desired quantity of the third liquid, as, for example, benzol, and for supplying to the system additional amounts of benzol to 85 replace the small quantities thereof which are lost by evaporation therefrom. The al- cohols and benzol are fed to the system in portions such that in the circulating system, 90 at any given time, there would be approxi- mately equal parts by weights of 95% alcohol and benzol but preferably a slightly smaller quantity of the benzol than of the 95% alcohol. The valved pipe 1 leads into a tail-box 3 which is connected by a liquid 95 sealed pipe 4 to a dehydrating column 5 which is constructed in any suitable manner but which may have, for example, a plural- ity of plates the same as in the case of the usual alcohol rectifying column. The col- umn 5 has at the bottom an inlet 6 and an outlet 6^a for steam for heating the column indirectly. Vapors are evolved from the column comprising approximately 74.1% by weight of benzol, 7.4% by weight of water, and 18.5% by weight of alcohol and absolute alcohol flows from the liquid sealed outlet 100 pipe 7. The evolved vapors pass out by means of a pipe 8 into a dephlegmator 9 which is connected by a liquid sealed pipe 10

105 110

to the top plate of the column. The dephlegmator is cooled in the usual way with the aid of water inlet and outlet pipes 11 and 12. The uncondensed vapors from the dephlegmator 9 pass into a condenser 13 through a pipe 13^a, the temperature in which is at approximately 64.9° C., said condenser being cooled by water passing through inlet and outlet pipes 14 and 15 and the condensate therefrom enters a vented sight-glass 16 from which a portion of the condensate passes through a valved pipe 17 to the pipe 10 and thence to the top of the column 5. The main portion of the condensate is conducted by a pipe 18 to a tail-box 19 and thence by a pipe 20 to a separating chamber 21. The liquid received in the separating chamber immediately separates into two liquid phases forming layers, the upper layer of which is rich in benzol but poor in alcohol and water, while the lower layer is rich in alcohol and water but poor in benzol. The composition of the respective layers is approximately as follows: The upper layer contains approximately 85.6% by weight of benzol, 2.8% by weight of water, and 11.6% by weight of alcohol, while the lower layer contains approximately 8.1% by weight of benzol, 40.6% by weight of water and 51.3% by weight of alcohol. The upper layer is conveyed by a vented pipe 22 having a liquid seal 23 back to the tower 5 while the lower layer passes by a vented pipe 24 to a scrubber 25. In order to remove the remainder of the benzol, water is introduced into the scrubber 25 by a pipe 26 thus producing therein two layers of liquid, the upper layer of which contains the remainder of the benzol. The benzol layer is conducted from the scrubber by a vented pipe 27 to the liquid seal 23 and thence to the tower 5, while the lower layer is conveyed through a vented liquid sealed pipe 28 to an alcohol rectifying column 29 having a steam inlet pipe 30 and an outlet 30^a in the usual way for indirect heating and a liquid sealed drawoff pipe 31 for water at the bottom of the column. The lower portion of the column 29 is maintained at a temperature of just above 100° C. The evolved alcohol vapors containing some water pass out of the top of the column through a pipe 32 to a dephlegmator 33, constructed substantially the same as the dephlegmator 9 and which is arranged to return the condensate therein to the top of the column 29 by a liquid sealed pipe 34. The vapors from the dephlegmator 33 pass through a pipe 35, the vapors in which are at a temperature of approximately 76° C., to a condenser 36 constructed the same as the condenser 13. The condensate from the condenser 36, which comprises approximately 95% alcohol enters a vented sight-glass 37 and a portion of the same passes back through a valved pipe 38 to the liquid sealed pipe 34 and thence to

the top of the column 29, while the remainder thereof enters a tail-box 39 and is conveyed therefrom by a valved pipe 40 direct to the liquid sealed pipe 23 and thence to the column 5. The apparatus is also arranged in an effective manner in that the portions thereof requiring observation are located upon an operating floor 41.

In carrying out my invention the alcohol containing water and the benzol is fed into the column 5, the lower portion of which is maintained at a temperature slightly below 78.4° C. The vapors of alcohol, water and benzol will be distilled from the top of the column 5 thus leaving behind absolute alcohol which passes out of the bottom of the column through the pipe 7. The evolved vapors pass into the dephlegmator 9, whence some of the condensate is returned to the topmost plate in the column 5 and at the same time a small portion of the condensate from the condenser 13 is also conveyed into the tower at the same point, thus sealing the uppermost plates in the column with a liquid of a constant composition and which is very close to the composition of the evolved vapors. This not only provides uniform conditions at the top of the tower but enables the apparatus to be conducted with a comparatively small quantity of benzol so that the condensate reaching the separating chamber 21 will be rich in the water to be removed. When the liquid condensate reaches the separating chamber 21 it immediately divides into two layers, the upper layer, comprised principally of benzol, being conveyed back to the tower 5, while the lower layer, comprised principally of alcohol and water but containing some benzol, is conducted to the scrubber 25 where water is added in the proportions of approximately one part by weight of water to one part by weight of the incoming liquid. This separates out the benzol into an upper layer which is conveyed back to the column 5, while the dilute alcohol is conducted to the alcohol rectifying column 29. This column is required merely to rectify the alcohol, said column at its lower portion being maintained at a temperature of approximately 100° C., the water from which passes out from the bottom of the column, while the alcohol, substantially 95% in strength, is collected as a condensate having a fixed composition and temperature, and as the benzol has been substantially entirely removed therefrom, the conditions in the upper portion of the column 5 are comparatively uniform so far as the character of the incoming alcohol is concerned. Furthermore, inasmuch as the bulk of the benzol is returned directly from the separating chamber 21 to the column 5, while the scrubbing is applied only to the small portion of the benzol recovered in the scrubber 25, the benzol is re-

turned to the column 5 in a drier form than would otherwise be the case and this also conduces to uniformity in the operation of the apparatus. For the same reason less

6 water is carried back into the column 5 and there is consequently a more effective separation of the alcohol from the water. By providing a system of this character in which the several parts of the system operate

10 without a great degree of dependence upon one another it is possible to conduct the apparatus with great uniformity of results and in such a way that the failure of any portion of the system to function tem-

15porarily would not interfere with the effective operation of the system as a whole. For these reasons, furthermore, it is practicable to obtain absolute alcohol with a continuously operating apparatus.

20 While I have described my invention above in detail I wish it to be understood that many changes may be made therein without departing from the spirit of the same.

25 By the term "scrubber" in the claims is meant a device for scrubbing the liquid from the separator so as to further separate the constituents by ordinary scrubbing action.

I claim:

30 1. An apparatus comprising a rectifier, a condenser connected thereto, a separating chamber connected to the condenser and a scrubber connected to the separating chamber.

35 2. An apparatus comprising a rectifier, a condenser connected thereto, a separating chamber connected to the condenser, a scrubber connected to the separating chamber and means for conveying liquids from the separating chamber and scrubber back to the rectifier.

40 3. An apparatus comprising a rectifier, a condenser connected thereto, a separating chamber connected to the condenser, a scrubber connected to the separating chamber, means for conveying liquids from the separating chamber and scrubber back to the rectifier and a second rectifier connected to the scrubber.

45 4. An apparatus comprising a rectifier, a condenser connected thereto, a separating chamber connected to the condenser, a scrubber connected to the separating chamber, means for conveying liquids from the separating chamber and scrubber back to the rectifier, a second rectifier connected to the scrubber, a condenser for the second rectifier, and means for conducting the condensate from the second rectifier to the first

50 rectifier.

55 5. An apparatus comprising a rectifier, a condenser connected thereto, a separating chamber connected to the condenser, a scrubber connected to said separating chamber and adapted to receive a condensate

therefrom, a second rectifier connected to said scrubber, a dephlegmator and condenser connected to the second rectifier so as to return a part of the condensate from said dephlegmator and last mentioned condenser 70 to the top of the second rectifier, and means for conveying the condensate from the second rectifier to the first rectifier.

6. An apparatus comprising a rectifier, a dephlegmator and condenser connected to the rectifier so as to return a portion of the condensate to the top of the rectifier, a separating chamber connected to said condenser and adapted to receive condensate therefrom, a scrubber connected to said separating chamber and adapted to receive condensate therefrom, a second rectifier connected to said scrubber, a dephlegmator and condenser connected to the second rectifier so as to return a part of the condensate to the top of 80 the second rectifier and means for conveying the condensate from the second rectifier to the first rectifier.

7. An apparatus comprising a rectifier, a condenser connected directly thereto, a separating chamber connected to the condenser, a return conduit from the separating chamber to the rectifier, means connected to the said chamber for further separating liquid obtained from said chamber, a conduit from 90 said means for returning separated liquid to said rectifier, a second rectifier connected to said means, a condenser connected to the second rectifier, and a return conduit connecting this condenser to the first-named 95 rectifier.

8. An apparatus comprising a rectifier provided with feed conduits near its top and heating means at its bottom, a condenser for the rectifier, a separating chamber and means for conveying the condensate from the condenser to the separating chamber, a second rectifier connected to the separating chamber, a condenser for the second rectifier, and means for conveying the condensate 100 from the second rectifier to the first rectifier.

9. An apparatus comprising a rectifier provided with feed conduits near its top and heating means at its bottom, a condenser for the rectifier, a separating chamber and means for conveying condensate from the condenser to the separating chamber, means connected to the chamber for further separating liquid obtained from said chamber, a conduit from said means for returning separated liquid to said rectifier, a second rectifier connected to the separating chamber, a condenser for the second rectifier, and means for conveying the condensate from the second rectifier to the first rectifier.

In testimony that I claim the foregoing, I have hereunto set my hand this 26th day of January, 1921.

JOHN A. STEFFENS.

Certificate of Correction.

It is hereby certified that in Letters Patent No. 1,586,718, granted June 1, 1926, to John A. Steffens, of Baltimore, Maryland, for an improvement in "Apparatus for Obtaining Absolute Alcohol," an error appears in the printed specification requiring correction as follows: Page 3, line 90, claim 7, strike out the word "directly" and insert the same to follow after the word "connected" in line 91; and that the said Letters Patent should be read with this correction therein that the same may conform to the record of the case in the Patent Office.

Signed and sealed this 13th day of July, A. D. 1926.

[SEAL.]

M. J. MOORE,
Acting Commissioner of Patents.
